US0D1029943S

(12) **United States Design Patent** (10) Patent No.: **US D1,029,943 S**
(45) Date of Patent: ** Jun. 4, 2024

(54) **GAME CONTROLLER FOR MOBILE DEVICES**

(71) Applicant: **Min Seob Han**, Seoul (KR)

(72) Inventor: **Min Seob Han**, Seoul (KR)

(**) Term: **15 Years**

(21) Appl. No.: **35/515,739**

(22) Filed: **Sep. 28, 2022**

(80) **Hague Agreement Data**

Int. Filing Date: **Sep. 28, 2022**

Int. Reg. No.: **DM/225096**

Int. Reg. Date: **Sep. 28, 2022**

Int. Reg. Pub. Date: **Dec. 9, 2022**

Primary Examiner — Mehri F Bajoul

(57) **CLAIM**

The ornamental design for game controller for mobile devices, as shown and described.

DESCRIPTION

1.1 is a perspective view illustrating a game controller for mobile devices, showing my new design;

1.2 illustrates a front side of the design;

1.3 illustrates a rear side of the design;

1.4 illustrates a left side of the design;

1.5 illustrates a right side of the design;

1.6 illustrates a top side of the design;

1.7 illustrates a bottom side of the design; and

1.8 illustrates a use state of the subject design.

The broken lines in reproduction 1.8 illustrate the environmental structure of the game controller for mobile devices that form no part of the claimed design.

1 Claim, 8 Drawing Sheets
